TOWEL DISPENSING CABINET

Roger I. Protas, Pittsburgh, Pa., assignor, by mesne assignments, to Blairstown Machine Products Company, Blairstown, Pa., a corporation of Pennsylvania

Application April 9, 1956, Serial No. 40,977

Term of patent 14 years

(Cl. D4—3)

Fig. 1.

Fig. 2.

Fig. 1 is a front elevation of a towel dispensing cabinet showing my new design; and

Fig. 2 is a side elevation of the cabinet of Fig. 1.

The side of the cabinet not disclosed in the drawing is substantially the same in appearance as the side shown.

I claim:

The ornamental design for a towel dispensing cabinet, as shown and described.
